CLAIM

(57) The ornamental design for an Advent manger, as shown and described.

DESCRIPTION

FIG. 1 is a top perspective view of an Advent manger, showing our new design;

FIG. 2 is a top plan view thereof;

FIG. 3 is a bottom plan view thereof;

FIG. 4 is a front elevation view thereof, with the back elevation view being a mirror image thereof; and,

FIG. 5 is a right side elevation view thereof, with the left side elevation view being a mirror image thereof.
